UNITED STATES PATENT OFFICE.

BAYARD E. TAYLOR, OF OAK PARK, ILLINOIS.

VEHICLE DOOR LOCK.

Application filed May 18, 1921. Serial No. 470,643.

To all whom it may concern:

Be it known that I, BAYARD E. TAYLOR, a citizen of the United States, and a resident of the village of Oak Park, in the 5 county of Cook and State of Illinois, have invented certain new and useful Improvements in a Vehicle Door Lock; and I do hereby declare that the following is a full, clear, and exact description of the same, 10 reference being had to the accompanying drawings, and to the numerals of reference marked thereon, which form a part of this specification.

In the assembling of automobile bodies 15 the doors have the door locks mounted therein before the doors are completely finished and before the same are hung. With the types of door locks usually used the inner handles or handle rods project through 20 and above the top edges of the doors and consequently are quite often bent or damaged before the doors are completely finished and hung in place. It is therefore necessary to remove part of the door up- 25 holstering from the inner side of a door to afford access to the damaged door lock so that the same may be removed to permit the damaged handle to be repaired or replaced. This invention relates to an im- 30 proved type of a vehicle door lock wherein the inner handle is adapted to be remov- 35 ably inserted into operative position within a door lock after the door lock is completely assembled and mounted in place within a completely finished door hung in place in 40 a vehicle body, thereby preventing bending or damage to the handle and making it unnecessary to remove a lock when once in place to replace the handle.

It is an object of this invention to pro- 45 vide a vehicle door lock of reduced cost and simplified construction wherein a number of the operating parts are constructed of stamped metal instead of castings and wherein the inner handle for retracting the locking bolt is adapted to be inserted and removed through the top of the lock whether the lock is mounted within a door or is unmounted.

It is also an object of the invention to 50 provide a vehicle door lock the inner han- 55 dle or lever of which may be readily re- moved or inserted into the lock when the locking bolt is in retracted position.

Another object of the invention is to pro- 55 vide a vehicle door lock wherein different

types of inner handles or levers may be inserted in place after the lock is mounted, the style of handle or lever used depending upon the make of the vehicle on which the 60 lock is mounted.

It is a further object of this invention to construct a vehicle door lock of metal stampings in place of castings to reduce the cost of production of the lock.

It is furthermore an object of the invention to construct a vehicle door lock having a removable inner handle or lever and wherein the latch bolt, the outer handle roll back and other parts are of stamped 70 construction instead of being cast, thereby permitting the lock to be more quickly manufactured and at a substantial saving.

Still another object of the invention is to provide a vehicle door lock of simplified 75 construction and reduced cost, said lock having a removable inner handle or lever, said lock furthermore adapted to be locked or unlocked from both sides of the door to permit retraction of the latch bolt and its 80 wedge member by the operation of either an outer handle or the removable inner handle.

It is an important object of this invention to provide a vehicle door lock of sim- 85 ple and effective construction wherein a latch bolt locking cam is held against accidental movement by a friction spring, and wherein the handle or lever for retracting the latch bolt is adapted to be inserted into 90 the lock after the lock has been completely assembled and secured in place within a completed vehicle door.

Other and further important objects of this invention will be apparent from the 95 disclosures in the specification and the accompanying drawings.

The invention (in a preferred form) is illustrated in the drawings and hereinafter more fully described.

On the drawings:

Figure 1 is a front elevation of a vehicle door lock embodying the principles of this invention and showing the removable lever for operating the lock mechanisms from the 105 inner side of the door.

Figure 2 is a rear elevation of the door lock mounted on a vehicle door with the lever hand grip removed.

Figure 3 is an enlarged detail front ele- 110 vation of the lock with the cover removed.

Figure 4 is an inner end view thereof.

Figure 5 is an enlarged fragmentary detail section taken on line 5—5 of Figure 2.

Figure 6 is a sectional view taken on line 6—6 of Figure 5.

5 Figure 7 is a fragmentary detail elevation of the latch bolt showing part of the lock mounting plate.

Figure 8 is an end elevation of the lock mounted in position in a vehicle door.

10 Figure 9 is a fragmentary sectional view of the lock illustrating a modified form of a stamped roll back.

Figure 10 is a sectional view thereof taken on line 10—10 of Figure 9.

15 Figure 11 is a detail front elevation of a modified form of door lock with the cover removed and with parts shown in section.

Figure 12 is a detail section taken on line 12—12 of Figure 11.

20 Figure 13 is a fragmentary detail section taken on line 13—13 of Figure 11.

Figure 14 is a detail section of the latching mechanism taken on line 14—14 of Figure 11.

25 As shown on the drawings:

The reference numeral 1 indicates a vehicle door provided on the inner side with a lock receiving recess and with openings or recesses 2 and 3 communicating with said recess, as illustrated in Figure 2.

The lock disclosed in Figures 1 to 8 inclusive, comprises a mounting plate or back plate 4 one end of which is bent at an angle to afford a flange 5 having screw openings

35 6 and a latch bolt opening therein. Secured in a stud or boss 7 formed on the mounting plate 4 is the inner end of a heavy coiled spring 8 the outer end of which projects upwardly and engages against a lever or arm

40 9 pivoted on a pin 10 integrally formed on one side of the inner end of a slidable bar 11. Integrally formed on the opposite side of the slidable bar 11 is a guide block or lug 12. The block 12 projects into and is slidable in

45 a guide slot 13 formed in a cover or casing 14 secured to the mounting plate 4 to enclose the operating mechanisms of the lock. The slidable movement of the slide bar 11 is limited by the lug 12 striking the casing 14 at the ends of the guide slot 13. The slide bar has integrally formed on the outer end thereof a beveled wedge 15 which is slidable through the opening in the flange 5. The wedge 15 is adapted by the inward movement of the slide bar 11 to move in a channel strap or saddle 16 rigidly secured on the outer surface of the mounting plate 4 and to the inside of the flange 5. Said strap 16 affords a guide for the latching members of

55 the lock. The strap 16 projects from the mounting plate outwardly through an opening 17 in the casing 14.

60 The wedge members 11—15 are cut away at the sides thereof to afford shoulders 18 adapted to contact the inner ends of the

flanges 19 integrally formed on opposite margins of a slidable stamped metal latch bolt 20. Integrally formed on the inner end of the latch bolt 20 is an upwardly directed arm 21 to the upper end of which is integrally connected two parallel arms 22 and 23. The arm 22 is uppermost and has the ends thereof bent toward the mounting plate 4 to form lugs or projections 24 and 25. The arm 23 is deflected at 26 to permit the same to form a guide member slidable in a longitudinal slot 27 provided in the casing 14. The inner end of the arm 23 is bent toward the mounting plate 4 to form a lug or flange 28. As illustrated in Figure 3 the upper end of the pivoted arm or lever 9 contacts the flange 25 of the upper arm 22 to hold the latch bolt 20 in projected position by the action of the control spring 8. The casing 14 is deflected inwardly toward the mounting plate 4 to afford a retaining plate 29 which serves to hold the coils of the main spring 8 in the same plane. The casing 14 is open below the outer edge of the sunken retainer plate 29.

To retract the latch bolt 20 to permit opening of the door 1 from the exterior of a vehicle, an outer door handle 30 is provided. The outer handle 30 has a stem secured

thereon, the inner squared end of which projects into a squared opening 31 formed in one end of a cast or forged dog or roll back

32 supported between the mounting plate 4 and the casing 14. The free end of the roll back 32 is in contact with the flange 24 of the upper arm 22 of the latch bolt, so that when the outer handle 30 is turned the roll back 32 forces the latch bolt 20 inwardly together with the wedge 15 since the shoulders 18 of

100 the wedge bar 11 are in contact with the latch bolt flanges 19.

To open the door 1 from the interior of a vehicle, an inner handle or lever 33 is provided. The inner handle or lever 33 is removable and may be inserted into the lock after the same is secured in place in the door 1 or before mounting of the lock, as desired.

The lever 33 is formed of a flat metal bar deflected or bent at 34 and having integrally formed on the inner end thereof a hook 35.

The other or outer end of the lever 33 has a threaded screw or shank 36 integrally formed thereon to removably receive threaded

110 thereon a hand hold or knob 37. Rigidly secured to the lower inner corner of the mounting plate 4 is a pin or headed stud 38 on which the hook 35 of the lever 33 is adapted to be removably engaged.

When the latch bolt is forced inwardly against the action of the main spring 8 the hooked end of the lever 33 is adapted to be projected

115 downwardly through the door recess or opening 2 and between the mounting plate 4 and the arm 23 of the latch bolt to permit the hook 35 to engage over the stud 38. The

120

125 The lever 33 is adapted to be projected downwardly through the door recess or opening 2 and between the mounting plate 4 and the arm 23 of the latch bolt to permit the hook 35 to engage over the stud 38. The

130

hand hold 37 is then threaded upon the screw shank 36 of the lever. The hand hold 37 may be secured on the lever shank 36 before the lever is inserted into the lock if desired. The lever 33 may be easily removed from the lock by retracting the latch bolt by operating the outer handle 30 or by pressing against the projecting end of the latch bolt when the door is open. The recess or opening 3 in the door 1 permits the hook 35 of the lever 33 to be moved into and out of engagement with the stationary stud 38 which serves as a pivot point about which the lever operates when operated to retract the latch bolt. When the removable lever 33 is in place it is in contact with the flange 28 of the latch bolt arm 23, as illustrated in Figure 3.

A locking device is provided to permit the latch bolt 20 to be locked in its projected position to prevent opening of the door by actuation of either the door handle 30 or the lever 33—37. For this purpose a third handle or thumb knob 39 is provided on the inner side of the door lock. The thumb knob 39 is rigidly secured on the projecting end of a stem or shank 40 on the inner end of which is integrally formed a head 41 disposed between the mounting plate 4 and the casing 14. Integrally formed on the periphery of the shank head 41 is a tooth or a radial projection 42 which is adapted to engage in a notch 43 provided in a dog or cam 44. The locking cam 44 is pivotally mounted adjacent the mounting plate 4 on a pin 45 secured to said mounting plate and projecting into an opening in the casing 14. Coiled around the pin 45 is a conical auxiliary spring 46 the base end of which frictionally seats against the locking cam 44. The other end of the spring 46 crosses the base end and engages beneath the saddle or strap 16 as illustrated in Figure 6. The locking cam 44 is provided with a notch 47 for the purpose of engaging the inner lower corner 48 of the latch bolt 20 when the latch bolt is projected and when the cam 44 has been turned into locking position by operation of the thumb knob 39.

Figures 9 and 10 illustrate a modified form of roll back which may be used in place of the cast or forged roll back 32. The improved roll back is of resilient or spring construction made of a steel stamping, one end of which is narrower than the other, and is bent to form a head 49. The base or wider end of the steel stamping is curled to form a spring 50 the end of which is adapted to engage in a slot provided in the inner squared end of an outer handle shank 51. The curled spring base 50 of the roll back has the ends thereof projecting into openings in the mounting plate and in the casing plate between which the roll back is mounted.

In the modified form of door lock illustrated in Figures 11 to 14 inclusive, the reference numeral 52 indicates a back or mounting plate, one end of which is bent at an angle to form a flange 53 having an opening therein 70 to permit the latching members to project therethrough. Secured in a slotted stud 54 on the mounting plate 52 is the inner end of a coiled main spring 55 the outer end of which projects upwardly and is engaged 75 against a lever or arm 56. The arm 56 is of stamped metal. One end of the stamped metal arm is bent over on itself to form a head 57. The opposite end of the arm 56 is wider than the head end and is provided 80 with a notch 58. The notched or bifurcated end of the arm 56 is engaged on a pin or lug 59 struck from a metal stamping or slidable plate 60. Integrally formed on the inner end of the slidable plate 60 is a tongue which 85 is bent to lie flat against the plate 60 to afford a guide block or lug 61 which projects into and is slidable in a longitudinal guide slot 62 formed in a cover or casing 63. The casing 63 is secured to the mounting plate 52 90 to enclose the operating mechanisms of the lock. The casing 63 is provided with flanges or walls 64, 65 and 66 which bear against the mounting plate 52. The inward movement of the slide plate 60 is limited by the 95 lug 61 striking the casing at the end of the guide slot 62. The end of the stamped metal slide plate 60 is curved upwardly and bent rearwardly and downwardly to afford a resilient or spring wedge 67. The wedge 67 100 is slidable in the opening in the flange 53 and is furthermore adapted to move through a channel strap or saddle 68 secured on the outer face of the mounting plate 52 adjacent the inner surface of the flange 52.

The wedge plate 60 is cut away at the sides thereof to afford shoulders 69 to contact the inner ends of flanges 70 integrally formed on the opposite margins of a stamped metal latch bolt 71. Integrally formed on the inner end of the latch bolt 71 is an upwardly directed arm 72 to the upper end of which is integrally connected two parallel arms 73 and 74. The arm 73 is uppermost and has the ends thereof bent toward the 110 mounting plate 52 to afford lugs or flanges 75 and 76. The arm 74 is deflected to permit the same to form a guide member slidably in a longitudinal slot 77 provided in the casing 63. The inner end of the arm 74 is 115 bent to form a lug or flange 78. As illustrated in Figure 11, the head end 57 of the arm 56 contacts the flange 76 of the upper arm 73 to hold the latch bolt in projected position.

To retract the latch bolt 71 to permit opening of an automobile door from the exterior of the vehicle, an outer handle is provided on the projecting end of a handle stem or shank 79. The outer end of the 130

handle shank 79 is slotted and projects through the mounting plate 52 and through an opening in the casing 63. A resilient or spring roll back is provided in the casing 5 and is constructed of a metal stamping, one end of which is bent to form a head 80. The other end of the metal stamping is curled to form a spring 81, the end of which is engaged through the slot in the handle 10 shank 79. The roll back head 80 is in contact with the flange 75 of the upper latch bolt arm 73, so that when the outer handle is turned the spring roll back will force the latch bolt 71 inwardly together with the 15 resilient wedge 67, since the shoulders 59 of the wedge plate 60 are in contact with the latch bolt flanges 70.

For opening a vehicle door from the interior of the vehicle, an inner handle or 20 lever 82 is provided. The lever 82 is removable and may be inserted into the lock either before or after the same has been mounted in place on a vehicle door. The lever 82 is formed of a curved flat metal bar, 25 the inner end of which is provided with a notch 83 or is hook shaped to permit the lever to be removably engaged on a pin or headed stud 84. The stud 84 is rigidly secured on the lower inner corner of the 30 mounting plate 52. To hold the notched inner end engaged on the stud 84 a plate spring 85 is secured at one end to the inner surface of the casing flange 65 while the free end of the spring engages against the 35 curved edge of the lever 82. The upper or outer portion of the lever 82 is twisted at 86 and bent to afford a U-shaped head 87 having thread apertures therein. Removably threaded through the apertures of the 40 lever head 87 is the threaded shank 88 on the outer end of which a handle or hand hold is secured.

A locking device is provided to permit 45 the latch bolt 71 to be locked in its projected position to prevent opening of the door by actuation of either the outer handle or the lever 82. A notched cam 89 is pivotally mounted on a pin 90 secured to the mounting plate 52. The locking cam is 50 adapted to be actuated by a tooth 91 formed on a shank 92. The shank 92 projects through the mounting plate 52 and is adapted to be operated from the interior of a vehicle by a thumb knob similar to the construction shown in Figure 5. The cam 89 is notched to permit the same when operated to engage against a corner 93 of the latch bolt 71.

The operation is as follows:

60 In the form of door lock illustrated in Figures 1 to 8 inclusive the main spring 8 pressing against the pivoted arm 9 acts to hold the latch bolt 20 and the wedge 15 in their projected latching positions. The lock 65 is adapted to be mounted in a vehicle door

1 without having the inner handle or lever 33 in place. The door may be completely finished and upholstered on its inner side to cover the door lock. The lever 33 may be inserted into the lock through the open upper end of the door recess or opening 2. When the lever is put into place the latch bolt 20 is retracted either by turning the outer handle 30 or by pushing inwardly 70 against the projecting end of the latch bolt. The hooked end of the lever is now inserted through the door recess 2 and into the lock between the mounting plate 4 and the latch bolt arm 23. The door recess 3 permits the hooked end of the lever to be positioned to allow the lever hook 35 to engage the pin or stud 38. The latch bolt 20 is now released and the spring 8 projects the same outwardly into latching position. The movement of the latch bolt into projected 75 position brings the arm flange 28 into contact with the lever 33. The lever 33 cannot be removed from the lock when the latch bolt is projected.

With the door 1 in closed position in a 80 vehicle body the latch bolt first moves into projected latching position and is followed by the wedge 15 which wedges against a flange of the door frame strike plate thereby holding the door rigidly in place in the door 85 frame to prevent rattling of the door. The wedge 15 is slidable with respect to the latch bolt 20 and under the impulse of the spring 8 is adapted to be projected into the space between the latch bolt 20 and a flange 90 of the door frame strike plate. The wedge 15 may wedge in any position of projection to take up the play between the latch bolt and the strike plate to obviate rattling of 95 the door.

With the locking cam 44 in release position, as shown in Figure 3, the closed door may be readily opened from the exterior of the vehicle by turning the outer handle 30 thereby causing the roll back 32 to press against the flange 24 to force the latch bolt 20 inwardly against the action of the spring 8. The flanges 19 of the latch bolt being in contact with the wedge bar 11, both the latch bolt and the wedge are simultaneously 100 retracted as a unit and the door may be swung into open position. Release of the outer handle 30 permits the stressed spring 8 to again force or shoot the latch bolt 20 and the wedge 15 outwardly through the 105 opening in the mounting plate flange 5.

To open the door from the interior of the vehicle the inner handle or lever 33 is pulled by means of the hand hold 37 thereby causing the lever to pivot on the stud 38 to engage the flange 28 to retract the latch bolt 20 and the wedge 15 against the action of the spring 8. With the operation of the lever 33 and the retraction of the latching members the door is swung outwardly into 110 115 120 125 130

open position. The handle 30 and the lever 33 may be operated independently of each other to retract the latching members. The rearward movement of the latch bolt and the wedge is limited by the stop 12 which slides in the casing slot 13. To lock the latching members in their projected positions to prevent opening of the door by operation of either the outer handle 30 or the inner handle lever 33, the thumb button or knob 39 is turned thereby causing the tooth 42 to rotate the locking cam 44 into a position wherein the notch 47 thereof engages the shoulder 48 of the latch bolt 20. The spiral conical spring 46 frictionally engages against one side of the cam 44 and holds the same against accidental movement out of a set position. The latch bolt is unlocked by operating the thumb knob 39 to cause the cam 44 to move out of engagement with the latch bolt shoulder 48.

If desired the resilient roll back 49—50 made of stamped metal may be substituted for the cast or forged roll back 32.

25 In the modified form of the door lock illustrated in Figures 11 to 14, the operation of the lock is substantially the same as that hereinbefore described. In this case however the arm 56, the roll back 80—81, 30 and the wedge are made of stamped metal instead of cast or forged metal thereby providing a vehicle door lock of less expensive construction. The lever 82 may be inserted into the lock after the lock is mounted in 35 place with a vehicle door. The lever is inserted into the lock between the mounting plate 52 and the latch bolt arm 74. The latch bolt 71 may be retracted from the outer side of the door by operating the outer 40 handle not shown but provided on the outer end of the handle shaft 79. The notch 83 of the lever 82 is engaged on the stud 84 and the spring 85 acts to hold the notched inner end of the lever in contact with said 45 pivot stud 84. When the latch bolt is released the spring 55 acts to project the latch bolt and move the latch bolt flange 78 into contact with the lever. The handle on the upper end of the shank 88 facilitates operation 50 of the lever from the inner side of the door. The spring construction of the lever head 87 locks the lower end of the shank 88 in an adjusted position with respect to the lever.

55 By producing the majority of the operating parts of the door lock of steel stampings instead of cast or forged metal, a lock of compact and inexpensive construction is provided.

60 The novel arrangement whereby the inner handle or lever of the lock may be inserted into the lock either before or after mounting of the same in a vehicle door permits one type of lock to be used in practically any style of open or closed vehicle

body constructions. The lever or inner handle may be threaded and bent to form to suit the particular type of door on which the lock is installed. Attention is directed to the fact that the inner handle or lever may 70 be removed or inserted into the lock when the same is unmounted or when the same is mounted in a door and completely covered by upholstering. The removing of the upholstering to uncover the lock is not necessary when a lever is to be mounted in place.

I am aware that numerous details of construction may be varied through a wide range without departing from the principles of this invention, and I therefore do not 80 purpose limiting the patent granted, otherwise than necessitated by the prior art.

I claim as my invention:

1. A vehicle door lock comprising a latch bolt, a wedge member, an arm pivotally 85 mounted on said wedge member and engaging said latch bolt, a spring engaging said arm for impelling said latch bolt and said wedge member outwardly into latching position, a handle for retracting the latch bolt 90 and wedge member against the action of said spring, and a lever adapted to be removably inserted into said lock when the latch bolt is retracted to afford a means for operating the latch bolt and said wedge 95 independently of said handle.

2. A door lock comprising a latch bolt, a wedge thereon having relative movement therewith, an arm pivoted on said wedge and contacting said latch bolt, a spring engaging said arm for impelling said latch bolt and said wedge outwardly into latching position, and a lever adapted to be removably projected into said lock to engage 100 said latch bolt to permit retraction of the latch bolt and said wedge when the lever is operated.

3. A door lock comprising a casing, a latch bolt therein, a wedge co-acting with said latch bolt, an arm pivoted on said wedge, a spring contacting said arm for projecting the latch bolt and said wedge into latching position, a roll back in said casing contacting said latch bolt, a handle for operating the roll back to cause retraction of the latch bolt and said wedge from one side of the door, a stud in said lock, and a lever adapted to be projected into said lock to removably engage said stud, 110 said lever adapted to be operated from the other side of the door to permit retraction of the latch bolt and said wedge independently of said handle.

4. A door lock comprising a latch bolt, a wedge associated therewith, an arm pivoted on said wedge and engaging said bolt, means contacting said arm for impelling the latch bolt and then the wedge outwardly into latching position, handles operable independently of each other for re- 125 130

tracting the latch bolt and the wedge from opposite sides of the door against the resistance of said means, and a locking mechanism in said lock adapted to be actuated 5 to lock said latch bolt and the wedge against retraction by said handles, one of said handles adapted to be disengaged from the lock to permit retraction of the latch bolt and the wedge from one side of the door 10 only.

5. In a vehicle door lock the combination with a movable bolt, means for projecting said bolt into latching position, a resilient mechanism for retracting the bolt 15 from one side of the door, and a handle adapted to be removably projected into the lock into an operating position engaged with said bolt to permit retraction of the bolt from the other side of the door independently of said resilient mechanism.

6. A lock comprising a stamped slideable latch, a stamped metal wedge slidably engaged therewith, a stamped metal arm pivoted on said wedge and contacting said 25 latch, a spring engaging said arm to hold the bolt and said wedge projected into latching position, a spring supported metal roll back in said lock contacting said latch, a handle for operating the roll back to 30 cause retraction of the latch and said wedge, and a lever adapted to be removably projected into said lock to engage said latch to permit retraction of the latch and said wedge independently of the operation of 35 said roll back and handle.

7. A lock comprising a stamped metal latch bolt, a stamped metal wedge slidably engaged therewith, means for operating said bolt and wedge so that they will have 40 a relative movement with respect to one another, and a roll back in said lock comprising a resilient portion and an integral head for retracting the bolt and wedge.

8. A lock comprising a stamped metal 45 latch bolt, a stamped metal wedge associated therewith, means for holding said bolt and wedge in projected latching position, a stamped metal roll back in said lock comprising a coil spring portion and an 50 integral head, and a handle connected with

said roll back spring portion, said handle adapted to be operated to operate said roll back to cause retraction of said bolt and wedge.

9. A lock comprising a stamped metal 55 latch bolt, a stamped metal wedge slideable thereon, a projection struck from said wedge, a stamped metal arm pivoted on said projection, a spring contacting said arm to hold said latch bolt and said wedge 60 in projected latching position, a stamped metal roll back in said lock comprising a coiled spring base and a head integral therewith, and a handle connected with said roll back spring base adapted to be operated 65 to cause retraction of the latch bolt and said wedge.

10. A door lock comprising a stamped metal latch bolt, a stamped metal wedge slideable thereon, a stamped metal arm 70 pivoted on said wedge and contacting said latch bolt, a spring contacting said arm for holding said latch bolt and wedge in projected latching position, a stamped metal roll back in said lock comprising a 75 coiled spring base and a head integral therewith and contacting said latch bolt, a handle connected with said roll back spring base adapted to be operated to cause retraction of the latch bolt and said wedge, 80 and a lever removably engaged in said lock and contacting said latch bolt, said lever adapted to be operated to cause retraction of the latch bolt and said wedge independently of said handle.

85 11. In a lock of the class described, the combination with a latching mechanism, of a stamped metal wedge slideably engaged therewith, means integral with said stamped metal wedge for limiting the movement of 90 said latching mechanism and said wedge, and a resilient roll back for retracting said latching mechanism and said wedge.

95 In testimony whereof I have hereunto subscribed my name in the presence of two subscribing witnesses.

BAYARD E. TAYLOR.
